UNITED STATES PATENT OFFICE.

CLAYTON E. FREDERICKSON, OF SAN FRANCISCO, CALIFORNIA, ASSIGNOR OF THREE-EIGHTHS TO WILLIAM H. STENGER, OF BERKELEY, CALIFORNIA, AND ONE-EIGHTH TO LOWELL J. HART, OF PALO ALTO, CALIFORNIA.

UNDERREAMER.

1,036,520.

Specification of Letters Patent. Patented Aug. 20, 1912.

Application filed October 12, 1911. Serial No. 654,846.

To all whom it may concern:

Be it known that I, CLAYTON E. FREDERICKSON, of San Francisco, in the county of San Francisco and State of California, have invented a certain new and useful Improvement in Underreamers, of which the following is a specification.

My invention is an improved tool for use in drilling and boring oil wells.

10 In practice a well tube or casing is forced into the well, and in order that the casing or tube may pass down, the well must be reamed out below the tube as it moves downwardly. In accomplishing this act, 15 the tools employed, not infrequently become jammed, broken, and lost, thereby rendering the operation of well drilling both uncertain and expensive, and furthermore delaying the operations until the "lost" tool is 20 recovered and removed from the well, or drilled into metallic dust or driven into a soft formation outside of the wall of the well.

It is therefore the principal object of the 25 present invention to provide an improved reaming tool that can be readily admitted or withdrawn through the well casing without delay, and without danger of jamming the tool in the casing.

30 The invention also consists in constructing the upper ends of the cutters with trunnions and forming slots or pockets in the supporting body, providing such body with grooves that communicate with the pocket 35 and placing the cutters in position by inserting the trunnion end of the cutters first in the main body and pushing the same into place, and then turning the cutters on their trunnions and dropping or forcing them 40 into the grooves and final resting place for the cutters, and furthermore the invention resides in providing a spring operated holding rod directly engaging the cutter in a manner that in the event of any accident by 45 breaking of the actuating rod or spring, the cutters will drop down the grooves in which the trunnions are located, until the trunnions rest at the bottom of the grooves, thus 50 making it impossible for the cutters to escape from the main body in case of accident.

More specifically the present invention is a modification of that disclosed in my co-

pending application filed September 19, 1911, Serial No. 650110, and as in that case, so in this, in applying my invention, I provide a body having cutter receiving chambers or pockets in which the cutters are so located and mounted as to project the cutting edges beyond the diameter of the body when in use to under-ream or undercut the well wall beneath the descending tube. The body and cutters are interlocked when in operation, in such manner however, that upon exerting an upward pull on the body, the cutters will unlock and telescope or fold 60 into the body to enable the reamer to be withdrawn through the tube whenever such action may be necessary or advisable. The cutters are also provided with removable cutting points to facilitate repairs, and 65 means are provided to hold the cutters and body in their proper interlocked relation during the operative function of the tool and thus prevent accidental disconnections taking place between the cutters and the 70 body.

The primary object of this invention is to eliminate what is known as the key for holding up the cutters in the devices heretofore proposed.

In its more subordinate nature, the invention includes those novel details of construction, combination and arrangement of parts, all of which will be first fully described and then be specifically pointed out in the appended claims, reference being had to the 80 accompanying drawings, in which,

Figure 1 is an elevation of the invention indicating its position in operation in a well, the well casing being shown in section. 90 Fig. 2 is a view at right angles to Fig. 1. Fig. 3 is a view similar to Fig. 1, showing how the tool may be removed from the work, in the event of breaking of the holding members, etc. Fig. 4 is an enlarged 95 central, vertical section of the tool in the position shown in Fig. 1. Fig. 5 is a central, vertical section showing how the cutters are connected with the holding rod block in assembling the parts, and also indicating how the cutters are held in position when the tool is being lowered into the well. Fig. 6 is a cross section on the line 6-6 of Fig. 4. Fig. 7 is an inverted plan view of 100

the tool. Fig. 8 is a detail perspective view of one of the cutters, the point being disconnected. Fig. 9 is a detail perspective view of the holding rod and its block.

5 In the drawings in which like numerals and letters of reference indicate like parts in all of the figures, 1 designates the main portion of the body, which has a threaded boss 2 and is bored at 3 to receive the spring 4 that surrounds the stem 5. The stem 5 projects into a bore 6, that communicates with the slot 7 which passes through the web 8, the web 8 separating the two cutter chambers 9-9. The extreme lower end of the body 1 is V-shaped as at 11 and is provided with an inverted V-shaped recess 12 at each side of the central V-shaped portion 11 to receive the correspondingly shaped head 13 of the cutters 14. Each cutter 14 has a lug 34 notched at 35 to enter the cross slot 10 in the holding block 36 and engage one of the projections 20 thereof, the block 36 carrying the rod 5 and operating in the slot 7. The side walls of the cutter chambers 9 are provided with L-grooves, one end 17 of each of which opens out at the side of the body, while the other end 18 is "blind" as indicated in Fig. 4. The grooves 17-18 receive the trunnion bearings 19 of the cutters 14. Each cutter 14 also has a "point" receiving recess 21, the upper wall of which is provided with a dovetail slot 22 to receive the dovetail 23 of the removable "point" 24. The "point" 24 is held in place by a pin 25 that passes through the cutter head 13 and the dovetail 22 as best shown in Fig. 4.

26 is a union-cap which is provided with a threaded pocket 27 for the boss 2, and it also has a bore 28 that communicates with 40 the pocket and receives the spring 4 and the rod 5. The union-cap 26 has a nut face 29 and a threaded pin 30 to screw into the operating stem or rod 31.

Operation: The well tube 32 having been 45 started into the well opening, the reamer is let down into position. This is accomplished by pulling the cutters 14 downwardly until the trunnions 19 rest in the "blind" ends of the grooves 18, at which time they are 50 folded in to lie within the diameter of the body end of the reamer, and they are held in this position against tension of the spring 4 by breakable pieces 33, of wood or other similar material, that are placed between 55 the shoulders 12 and 13 as best indicated in Fig. 5. The tool is then lowered through the well tube 32, and when the cutters engage the bottom of the well opening the rods 33 will break, and permit the spring 60 4 to draw the cutters into the operative position indicated in Fig. 4, the spring 4 being aided in this function by the weight of the body 1 and its carried parts. When it is desired to remove the tool from the well, 65 it is only necessary to draw up on the stem

31, when the inclined faces 39 of the cutters will engage the lower end of the well tube and be forced to telescope into the diametrical dimension of the body 1, and thereby readily pass through the well tube without danger of sticking or jamming. 70

In order that the cutters may be entered into position, the trunnions are flattened or cut away as at 40, so that they may be inserted, as indicated in dotted lines in Fig. 5. 75

From the foregoing description taken in connection with the accompanying drawings, it is believed the complete construction, operation and advantages of the invention will be manifest to those skilled in the art, and I desire it understood, that the forms disclosed in the drawings are the preferred arrangements, although, I do not wish to be limited thereto. 80

What I claim is:—

1. In an under-reamer, a body portion having radial chambers, the side walls of which are provided with grooves, cutters mounted in said chambers and having trunnions to enter said grooves, said body portion at its lower extremity having an interlocking face, said cutters each having interlocking faces to interlock with said body face, and a holding rod having a block, and projecting lugs on said cutters to engage 95 said block for continuously tending to hold said cutters interlocked with said body, said trunnions and said grooves including means to prevent disconnection between said body and cutters in the event that said lugs break 100 or said continuously tending means fails to act. 105

2. In a reamer, a body having radially disposed cutter receiving chambers, the side walls of said chambers having L-grooves one end of which opens outwardly and the other end is "blind," cutters having body portions held in said chambers and including trunnions mounted in said grooves, said cutters having heads, a spring actuated rod 110 device connecting with and continuously tending to move said cutters upwardly to bring said cutter heads into engagement with the under-face of said body, the cutter heads and said body-face having inter-projecting portions, said rod device including a block, and said cutters having lugs to engage said block, thereby connecting said rod device with said cutters. 115

3. In an under-reamer, a body portion 120 having radial chambers, the side walls of which are provided with grooves open at one end, cutters mounted in said chambers and having portions to enter said grooves, said body portion and said cutters having 125 interlocking faces, said cutters being foldable into the body, each of said cutters having a projecting lug, means engaging said lugs and continuously tending to hold said cutters interlocked with said body, said 130

grooves having a restricted entrance, and said trunnions having cut away portions in virtue of which said trunnions may be entered into said grooves when said cutters are in one position only, substantially as shown and described.

4. In a reamer, a body having radially disposed cutter chambers, the side walls of which have L-grooves, one end of each of which grooves opens outwardly and the other end is "blind," cutters having body portions held in said chambers and including trunnions mounted in said grooves, a spring actuated rod device, said rod device including a block having a slot, said cutters including projecting lugs for entering said slot and engaging said block, said spring actuated rod device serving to continuously tend to move said cutters upwardly to bring said cutters into engagement with said under body, substantially as shown and described.

5. In an under-reamer for oil wells, a main body having a radial cutter chamber or pocket, a cutter mounted in said pocket and having a projecting head, said cutter and body having interlocking portions to register with one another when said cutter is in its working position, a spring actuated rod device for holding said cutter in its working position and including a slotted block, said cutter including a projection to enter said slotted block and engage therewith, said cutter having trunnions and said main body having grooves to receive said trunnions, one end of each of said grooves being "blind" to retain said cutter in the event that it becomes disconnected from said block.

40 6. In an under-reamer for oil wells, a main body having a radial cutter chamber or pocket, a cutter mounted in said pocket and having a projecting head, said cutter and body having interlocking portions to register with one another when said cutter is in its working position, a spring actuated rod device for holding said cutter in its working position and including a slotted block, said cutter including a projection to enter said slotted block and engage therewith, said cutter having trunnions and said main body having grooves to receive said trunnions, one end of each of said grooves being "blind" to retain said cutter in the event that it becomes disconnected from said block, and releasable means for holding said cutter folded and against the tension of said spring actuated device within the diametric dimension of said body.

60 7. In an under-reamer, a body portion having a cutter chamber, the side walls of which are provided with grooves the lower ends of which are closed, a cutter mounted in said chamber and having trunnions to enter said grooves, said body portion and

said cutter having interlocking faces, and means continuously tending to hold said cutter interlocked with said body, said continuously tending holding means comprising a spring actuated rod device including a slotted block, and said cutter having a lug to enter said slotted block, said block having a projection and said lug having a notch to receive said projection, substantially as shown and described.

75 8. In an under-reamer, a body portion having a cutter chamber, the side walls of which are provided with grooves the lower ends of which are closed, a cutter mounted in said chamber and having trunnions to enter said grooves, said body portion and said cutter having interlocking faces, and means continuously tending to hold said cutter interlocked with said body, said continuously tending holding means comprising a spring actuated rod device including a slotted block, and said cutter having a lug to enter said slotted block, and means for interlocking said lug with said slotted block.

90 9. In an under-reamer, a body portion having a cutter chamber, the side walls of which are provided with grooves, a cutter mounted in said chamber and having trunnions to enter said grooves, said body portion and said cutter having interlocking faces, and means continuously tending to hold said cutter interlocked with said body, said grooves and said trunnions coöperating to hold said cutter connected with said body, and said grooves having provisions to retain said cutter in connection with said body irrespective of said means that continuously tends to hold said cutters interlocked with said body, said continuously actuating cutter holding means including a rod and block device, and said cutter having a projecting lug to engage the block of said block device, substantially as shown and described.

95 10. In an under-reamer, a body having a cutter receiving chamber opening at the side, the side walls of said chamber having grooves, one end of each of which opens outwardly and the other end is "blind", each of said grooves having its entrant end restricted, a cutter having a body portion held in said chamber and including trunnions mounted in said grooves, said trunnions having cut away portions to enable said trunnions to enter said restricted entrant ends of said grooves when said cutters are in one position only, said cutter having a head, said cutter-head and said body having interprojecting portions to interlock said cutter and body, and yieldable means for holding said cutter interlocked with said body, said yieldable means including a spring actuated rod device that includes a slotted block, said cutter having a projecting lug to enter and engage said slotted

110 115 120 125 130

- block and interlock therewith, said grooves and said trunnions preventing disconnection of said cutter from said body in the event that said yieldable means becomes disconnected from said cutters.
11. In an under-reamer, a body having a cutter receiving chamber opening at the side, the side walls of said chamber having grooves, one end of each of which opens outwardly, a cutter having a body portion held in said chamber and including trunnions mounted in said grooves, said cutter having a head, said cutter-head and said body having interprojecting portions to interlock said cutter and body, and yieldable means for holding said cutter interlocked with said body, said body grooves having provisions for retaining said cutter in connection with said body upon failure of said last named means to act, said last named means including a spring actuated rod and block device that includes a slotted block, and said cutter having a projecting lug to enter and interlock with said slotted block, substantially as shown and described.
12. In an under-reamer a supporting body having a cutter chamber, a cutter removably held in said chamber, resilient means for retaining said cutter in operative position, and means for retaining said cutter in connection with said body in the event that said resilient retaining means becomes broken or inoperative, said resilient retaining means comprising a spring actuated rod and block device that includes a slotted block, said cutter having a lug to enter the slot of said slotted block, and means for interlocking said lug with said slotted block, said cutter retaining means comprising grooves in said body having blind lower ends and trunnions on said cutters to lie in said blind ends in the event that said resilient retaining means becomes inoperative.
13. In an under-reamer a supporting body having a cutter chamber, a cutter having a lug and removably held in said chamber, resilient means engaging said lug for retaining said cutter in operative position, and means for retaining said cutter in connection with said body in the event that said resilient retaining means becomes broken or inoperative, a removable cutter point for said cutter and means for removably securing said cutter point in position, said cutter retaining means comprising grooves in said body having blind lower ends and trunnions on said cutters to lie in said blind ends in the event that said resilient retaining means becomes inoperative.
14. In an under-reamer for oil wells a supporting body having a cutter chamber or pocket opening outwardly, a cutter mounted in said pocket and having trunnions, said body having a set of trunnion receiving grooves, said cutter having a head, said cutter head and said body including interlocking portions to register with one another when said cutter is in its working position, a spring actuated rod and block device for holding said cutter in its working position, said cutter having a projecting lug to engage said block, said trunnions and grooves coöperating with one another and including means to retain said cutter in connection with said body at all times while the tool is in the well and irrespective of the connection between said cutter and said block, in virtue of which the breaking or failure to act of said spring actuated rod device and its connection with the cutter will not cause a disconnection of said cutter from said body.

CLAYTON E. FREDERICKSON.
